UNITED STATES PATENT OFFICE.

JOHN A. SCHEFFEY, OF COLUMBUS, OHIO.

RIVET-CUTTING MACHINE.

Specification of Letters Patent. Patented Oct. 23, 1917.

1,243,765.

Application filed October 7, 1915. Serial No. 54,682.

To all whom it may concern:

Be it known that I, JOHN A. SCHEFFEY, a citizen of the United States, residing at 259 Willow Ave., in the city of Columbus, 5 in the county of Franklin and State of Ohio, have invented a new and useful Rivet-Cutting Machine for what is practically called bursting rivet-heads.

This invention is particularly directed to 10 a type of machine which may be readily transported so that it may itself be taken to the work, rather than to have the work brought to the machine.

In this connection, the main object of my 15 invention resides in the provision of a structure whereby the severing bits may be moved toward and away from each other through the operation of a main drive shaft, it being unnecessary to reverse the direction of rotation of this drive shaft in order to accomplish the movement of the bits 20 in either direction. In this manner, considerable trouble is overcome, in that the machine may be attached directly to the 25 standard machines now in use.

Still a further object of the invention resides in the specific supporting structure of the bit-supporting jaws, as well as the specific structure for accomplishing the reversal in movement of these jaws without reversing the main driving power.

The preferred embodiment of my invention is shown in the accompanying sheets of drawings, in which similar characters of 30 reference designate corresponding parts, 35 and in which:

Figure 1 is a view in side elevation showing my improved type of rivet cutter,

Fig. 2 is a section taken on line 2-2 of

Fig. 1,

Fig. 3 is a section taken on line 3-3 of Fig. 1,

Fig. 4 is a view looking from the right of Fig. 1,

Fig. 5 is a view in perspective showing 45 one of the jaw members, and,

Fig. 6 is a view in perspective of one of the bits.

In these several views, there is shown a 50 pair of jaw members 1 and 2 supported at their front ends through the medium of a pair of links 3. These links are pivotally attached at their opposite ends, as shown at 4 and 5, to the jaws 1 and 2 respectively.

55 These jaws further carry a pair of bits 6

at their forward ends, whose biting edges are designed to be in alinement to grip the rivet or bolt to perform the shearing action. Both bits are rigidly held in place by means of the U-shaped clevis structures 7 held in 60 place through the medium of the cross plate 8 and nuts 9. The rear ends of both of the bits are bifurcated, as shown, and it is into these bifurcated portions that the spring element 10 is designed to seat. This spring 65 element forms a supplemental structure for holding the biting edges of the bits 6 in alinement, the spring itself having a hinged joint made as is shown at 11 and being rigidly connected to the rear end of the 70 jaws, as is shown at 12. By means of the rigid connection 12, the jaws are prevented from coming out of alinement with each other in the plane of Fig. 1, whereas the seating of this spring in the bifurcated ends 75 of the bits prevents their lateral shifting.

The mechanism for moving these bits toward and away from each other, will now be described. The rear end of each jaw member is bifurcated and also formed with 80 a transverse bearing to pivotally receive a bearing member 13, these bearing members being bored vertically to receive the screw shaft 14. The lower end of this screw shaft is threaded, as shown at 15, and enters a 85 threaded bore in the lower bearing member 13, while the intermediate and upper portions of the screw shaft are of square formations of different sizes, as is shown. The upper end 16 fits in a bushing 17 rotatably 90 secured in the upper bearing member 13 and directly beneath this bearing portion is a thrust bearing designated in its entirety by the reference numeral 18. Also secured to the upper squared portion of the screw shaft 95 15 is a bevel pinion 19, which meshes with a complementary gear 20 on the main drive shaft 21. This main drive shaft is suitably journaled in a yoke member 22 which is suitably supported from a bolt 23 carried by 100 the top side of the upper jaw member 1. This bolt member passes through a pair of suitable supporting clips 24 carried by the rear end of the upper jaw 1 and the connection of the bolt 23 with these supporting 105 clips is one which permits of a slight shifting back and forth, as will be presently described. The inside end of the main drive shaft 21 is also journaled in a cross piece 24 forming a portion of a horizontal yoke 25. 110

The forwardly projecting legs 26 of this yoke are attached to the vertical guide pieces shown at 27, whereby the jaw members are additionally guided in their movement. By means of the two yokes 22 and 25, a supporting frame for the drive mechanism is had. The bevel gear 20 already described, is loosely mounted upon the drive shaft 21, but its hub is provided with a ratchet face shown at 28 designed to coöperate with a complementary ratchet hub 29 on the bevel gear 30. This latter gear is in turn rigidly mounted upon the shaft 21 and at times is designed to mesh with the bevel pinion shown at 31 and being mounted upon the drive shaft 14. The drive shaft 21 may be operated by hand or may be coupled with any suitable driving power, so that when it rotates in a right hand direction, and the gears are in the position shown in Fig. 2, the gear 30 is rotated and because of its rotation and the ratchet clutch between it and the gear 20, this latter is also rotated. This gear 20 is in mesh with the pinion 19 and, therefore, the screw shaft 14 is operated to cause a movement of the jaws in one direction. Should it be desired to cause a reversal in movement, the operating handle shown at 32 is grasped and because of its pivotal mounting, as shown at 33, and its forked engagement with the grooved hub portion 34 of the gear 20, it may be moved out of mesh with the pinion 19. Similarly, the operating handle 35 is shown as being pivotally supported at 36 and its forked end operates in the grooved hub 37 of the pinion 31, so that after the gear 20 has been moved out of mesh with its pinion 19, the handle 35 may be operated to move the pinion 31 into mesh with the gear 30. In this manner, a reversal in the direction of movement of the jaws is obtained without reversing the direction of rotation of the drive shaft 21. The horizontal cross piece 38 of the yoke member 22 passes beneath the collar 39 located on the screw shaft 14, beneath the pinion 31. This collar is rigidly secured to the screw shaft and, therefore, as the shaft 14 moves down through the lower bearing block 13, the upper jaw 1 is given a downward movement, while the lower jaw 2 is given an upward movement.

In order to cause the operating handles 32 and 35 to remain in their adjusted positions, I have split the handle portions, as is shown in Figs. 1 and 3, the split portions of these handles operating through the slotted guide member 40. These split portions are somewhat resilient and when they are sprung apart, they resiliently engage the slotted walls of the members 40. When it is desired to shift the gears, the handle portions must be first pressed toward each other and then shifted. Release will again cause

a frictional holding between the handles and the members 40 in a manner which must be apparent.

From the foregoing description, it will be apparent that the biting ends of the jaws may be moved toward or away from each other by the rotation of the main drive shaft 21 continuously in the same direction. The jaws themselves pivot about the pivot points 4 and 5 and because of the pivotal connection of the screw shaft 14 through the medium of the bearing members 13, this pivoting action places no strain whatever upon this screw member. When the jaws are moved, the screw member moves back and forth to a very slight extent and to permit this, the connection of the bolt 23 supporting the yoke member 22 is made sufficiently loose in its passage through the supporting clips 34. In order that the device may be readily handled, it may be swung from a suitable crane and attached thereto, through any one of the attaching holes 41 in the upper jaw member. These holes are so arranged that when the center one forms the point of support, the tool is in substantially a horizontal position, while attachment through either one of the other two, will incline the tool to make it point up or down. From this, it will be apparent that I have provided a tool in which extremely high biting pressure may be had and further, that the tool may be operated with marked convenience, in that the continuous rotation of the drive shaft does not affect either the movement up or down of the jaws.

What I claim is:

1. A rivet cutting machine comprising a pair of jaw members, bits on the ends of said jaw members, means for pivotally supporting the front ends of said jaw members, said bits projecting to the rear of said pivotal mounting, and being bifurcated at their rear ends, spring arms hinged together and rigidly secured at their rear ends to said jaw members and operatively engaging the bifurcated ends of said bits to maintain said bits in alinement, and means engaging the rear ends of said jaws for moving said bits together.

2. A rivet-cutting machine comprising a pair of jaw members supported to permit their front ends to travel toward each other, bits on the front ends of said jaws, a drive shaft, a screw shaft operatively connected between the rear ends of said jaws so that rotation thereof will cause movement of the rear ends of said jaws toward or away from each other, and a driving mechanism between said drive shaft and said screw shaft operable to rotate said screw shaft in either direction for the same rotation of said drive shaft.

3. A rivet cutting machine comprising a pair of jaw members supported to permit

their free ends to travel toward each other, bits on the front ends of said jaws, a drive shaft, a pair of separable bevel gears on said drive shaft, clutch mechanism between 5 said gears, a screw shaft between the rear ends of said jaws, a pair of spaced bevel gears on said screw shaft, one for each of said first named bevel gears, and means whereby one gear on said screw shaft may 10 be thrown into mesh with one gear on said drive shaft when the other two are out of mesh and vice versa.

4. A rivet cutting machine comprising a pair of jaws supported to permit their front 15 ends to travel toward each other, bits on the front ends of said jaws, a drive shaft, a screw shaft, a bearing block in the rear a screw shaft, a bearing block in the rear end of each jaw member in which said screw shaft is journaled, each block being pivotally mounted in said jaws at right angles to 20 said screw shaft, and means operating between said drive and screw shafts for turning said screw shaft in either direction of rotation for moving said jaw members to 25 ward or away from each other.

5. A rivet cutting machine comprising a pair of jaw members supported to permit their front ends to travel toward each other, bits in the front ends of said jaws, a drive shaft, a pair of bevel gears on said drive 30 shaft, one rigidly mounted thereon and the other slidably mounted thereon, a clutch mechanism between said gears, a screw shaft between the rear ends of said jaws, a pair of spaced bevel gears on said screw shaft, 35 one being rigidly mounted thereon and the other slidably keyed thereon, and means whereby the movable gear on said screw shaft may be thrown into and out of mesh with the rigidly mounted gear on said drive 40 shaft and whereby the movably mounted gear on said drive shaft may be moved into and out of mesh with the permanently mounted gear on said screw shaft.

Columbus, Ohio, October 5, 1915.
